[57] CLAIM

The ornamental design for a surround concrete panel mold, as shown and described.

DESCRIPTION

FIG. 1 is a perspective view of the surround concrete panel mold according to this invention;

FIG. 2 is a top plan view;

FIG. 3 is a side elevational view;

FIG. 4 is a bottom view of the surround mold according to the present invention; and

FIG. 5 is a cross-sectional view taken along the lines 5—5 of FIG. 1 showing the interior side configuration facing the center cavity.
